Ward Cross & Smith

UNITED STATES PATENT OFFICE.

WILLIAM J. BAXTER, OF NEW YORK, N. Y.

METHOD OF TREATING COTTON FABRIC.

Application filed October 15, 1924. Serial No. 743,740.

To all whom it may concern:

Be it known that I, WILLIAM J. BAXTER, a citizen of the United States, and resident of the city of New York, in the county and 5 State of New York, have invented certain new and useful Improvements in Methods of Treating Cotton Fabric, of which the following is a specification.

The invention relates to method of treating 10 cotton fabric, and more particularly to the method of printing and finishing cotton fabric to simulate or resemble in appearance French flannel of the character used for shirtings having threads of contrasting 15 color woven therein.

In my copending application Serial No. 20 703,711, filed April 2, 1924, for printed cotton fabrics, I have described a cotton fabric printed so as to resemble French flannel of the type or pattern which has threads of 25 contrasting color appearing at somewhat irregular intervals over the surface of the fabric to give the appearance of rather indeterminate fine spots and streaks or streaky zones. As pointed out in said application, this was accomplished, briefly stated, by printing over the surface of the cotton fabric fine dots, preferably irregularly grouped and of somewhat irregular character, to 30 produce a soft toned stippled effect or ground tone with streaks or streaky zones of a somewhat darker shade extending irregularly over the ground tone, the streaks extending irregularly over the ground in the 35 same general direction and of varying widths and soft and somewhat blurred in appearance.

In my copending application Serial No. 40 743,741 filed on even date herewith, for printed cotton fabrics, I have described a cotton fabric printed to simulate or resemble French flannel of the character in which the colored threads extend in rather fine closely spaced diagonal lines across the length of 45 the fabric. For example, fine blue diagonal lines alternating with fine uncolored diagonal lines. As pointed out in said specification, due to difference in texture between cotton and flannel, it is impossible to 50 simulate this appearance by simply printing the fine solid or substantially solid colored lines diagonally across the fabric; and briefly stated, this character of French flannel was simulated in cotton fabric as described in said last specification, by print-

ing on the fabric the above mentioned stippled ground tone, except for fine closely spaced parallel lines of the surface running diagonally over the fabric, which lines are substantially free or sufficiently free of said 60 color to produce a contrast between the stippled ground and the said lines to give a serge-like effect. It was also pointed out in said specifications that to further simulate the flannel-like effect the printing was 65 done on grey cotton fabric—i. e., unbleached or only partly bleached fabric, and in addition thereto the fabric was given a soft finish preferably produced by roughening the surface of the flannel after the print- 70 ing.

The object of the present invention is the 75 production of cotton fabrics to simulate colored French flannel, such for example as the types above described.

The invention consists in the novel method of printing and treating cotton fabric to produce cotton fabric simulating colored French flannel of the character used for shirtings. The method will be described 80 according to the preferred manner of carrying out the same, and will be more particularly pointed out in the appended claims.

Further objects and advantages of the invention will more fully appear from the 85 following description taken in connection with the accompanying drawings forming a part of this specification and which illustrate by way of example two flannel-like patterns or effects that may be produced 90 on cotton fabric according to this invention.

Fig. 1 illustrates a printed cotton fabric having a flannel-like effect, produced according to the present invention; and

Fig. 2 illustrates either a printed cotton 95 fabric with a different flannel effect produced according to this invention, or it may illustrate the back of the fabric the front of which is illustrated by Fig. 1.

It will be observed from these figures that 100 the soft stippled ground tone is produced by the printing of dots 1 to give the desired effect, and that the serge-like effect is produced by the fine uncolored or sparsely colored diagonal lines 2, and the streaks or streaky zones by denser massing of the color 105 as shown at 3.

According to the preferred manner of producing flannel-like effects such by way of 110 example as those above described and illus-

trated, I take grey cotton fabric, i. e., cotton fabric that is unbleached or only partly bleached so as to have a grey tone as distinguished from a clear white tone, and I 5 then print on said grey fabric a pattern to represent or simulate colored French flannel, after which I give the cotton fabric a soft finish by somewhat roughening the surface of the cotton fabric. For example, in the 10 case of printing a fabric to obtain the stippled ground tone with serge effect, the printing roller is made with the fine stipple dots formed on its surface and suitably grouped to give the desired stippled effect, 15 such dots being grouped in between a series of fine diagonal raised portions of the roller which are free or substantially free of the indentations which print the dots, so that when the printing is done the uncolored or 20 sparsely colored fine lines appear as fine parallel diagonal lines across the fabric as shown in the drawings.

If it is desired to produce the streaks or 25 streaky zones as shown at 3 in Fig. 1, these may also be formed on the same roller by more closely massing the indentations in the roller which carry the color for producing these streaks or streaky zones. If 30 it is desired to have the streaks of different color from the stippled ground, or if it is desired to have the stippled ground consisting of two sets of dots of different but 35 blending colors then, it will be necessary to provide a second roller for the second color, as is well understood in printing operations, but it is more difficult to obtain the desired effect with the two colors, and a one color or one printing operation gives 40 highly satisfactory effects.

If it is desired to have a linear overprint 45 effect such as bold stripes or a checkered effect as it usual in some French flannels, these are usually of a different color from the ground, and in that case a second roller will be provided and a second printing operation.

Fabrics produced according to this process can be made to very closely simulate French flannels such as those used for shirtings, and they are highly desirable due to the great 50 reduction in cost of cotton over wool, and also because they are much cooler for summer wear. The "outing" effect of the French flannel can therefore be obtained at greatly reduced cost, and with more comfort 55 to the wearer in warm weather.

While I have illustrated by way of example two particular types or patterns of fabric simulating French flannel, I do not wish to be understood as limiting the method 60 to the production of these particular types, or otherwise than indicated in the appended claims, in which I aim to cover any modifications of the invention within the spirit and scope of the same.

Having thus described my invention, what I claim as new and desire to secure by Letters Patent, is:

1. Method of treating cotton fabric to resemble in appearance French flannel of the 70 character used for shirtings having threads of contrasting color woven therein, which comprises taking grey cotton fabric, printing thereon to represent said colored French flannel and somewhat roughening 75 the surface of the cotton fabric to give a soft finish thereto to enhance the flannel-like characteristic of the fabric.

2. Method of finishing and printing cotton fabric to represent French flannel of the 80 character used for shirtings having threads of contrasting color woven therein, which comprises taking a grey cotton fabric, printing a pattern thereon to represent said colored French flannel, including a stipple 85 effect ground tone, and somewhat roughening the surface of the fabric to give a soft finish thereto to enhance the flannel-like characteristic of the fabric.

In testimony whereof I have signed my 90 name to this specification,

WILLIAM J. BAXTER,
